UNITED STATES PATENT OFFICE.

OLIVER J. MOUSSETTE, OF NEW YORK, N. Y.

ACETYLENE-GAS GENERATOR.

SPECIFICATION forming part of Letters Patent No. 624,846, dated May 9, 1899.

Application filed October 24, 1898. Serial No. 694,425. (No model.)

To all whom it may concern:

Be it known that I, OLIVER J. MOUSSETTE, a citizen of the United States, residing at New York, (Rockaway Beach,) in the county of 5 Queens and State of New York, have invented new and useful Improvements in Acetylene-Gas Generators, of which the following is a specification.

By means of this invention a generator is obtained which is simple in construction and reliable in operation, as set forth in the following specification and claims and illustrated in the annexed drawings, in which—

Figure 1 is a sectional elevation of the generator. Fig. 2 is a sectional plan view of Fig. 1.

In the drawings is shown a fixed or ring-shaped bottom portion 1, to which is secured or screwed a removable bottom 2, which is shown with a handle 3. The bottom 1 carries two shells or walls 4 and 5, which form a liquid or water seal when the space between these walls is supplied with liquid, as water, or preferably oil, as the latter does not freeze and is thus serviceable if the generator should be exposed.

The gasometer is shown with its top or roof at 6 and its side 7 dipping into the seal 4 5, such gasometer rising and falling as it fills or empties. The material or carbide can be 30 stored in holder 8, mounted directly on the gasometer, so as to rise and fall therewith. An outlet 9 is secured directly to holder 8 and extends through gasometer 6 to deliver material into the liquid in reservoir 10.

35 The door or doors 11 normally close the outlet 9, suitable closing means, such as a spring 12, being employed. The door 11 has an arm 14, and from the reservoir 10 or its bottom 2 rises a standard 15, practically of tubular form and open or broken at its lower portion or end to allow the liquid in the reservoir free passage under or through such standard. As the gasometer exhausts and sinks with the holder 8 the arm 14 contacts 40 with standard 15 to open door or valve 11 and allow material to drop from the holder into the reservoir, whereupon a fresh charge of gas is generated, which causes the gasometer to rise and free arm 14 from contact with 45 standard 15. The door then closes to shut off further discharge from hopper until the gasometer again exhausts and sinks.

The gas-pipe 16 enters the gasometer outside or clear of reservoir 10 and can feed from the gasometer and is shown with branches 17 and 18, which latter can be shut off by valve 19 and is generally not used in case the generator is transportable or not fixed in position. The pipe 17 is shown rising along the outside of shell 4 and of its superstructure 55 20, which is shown as a continuation of and can be closed like shell 4, but is preferably broken or open to give access to holder 8 or its cover 21.

The superstructure 20 is shown with rim 65 or top 22, the pipe 17 leading into a chamber or channel 23 in such top. When the cap 24 is screwed or placed on the top 22 and its pipe 25 communicates with passage 23, the gas passes through pipe 25 to nipple 26, adapted for applying a burner or utilizing the gas.

The reservoir 10 can be cleaned or provided with liquid by unscrewing the bottom 2, carrying this reservoir. The removal of bottom 2 can be avoided by means of pipe 27, leading into reservoir 10 and branching to a filling and safety tube 28 and to a discharge or cleaning tube 29, which can be closed by valve 30. The filler 28 is of such height that the reservoir 10 can be filled therethrough to 70 proper level, but not to overflow. This filler 28 also acts as a safety-tube, since if excessive pressure occurs in the gasometer such pressure acting on the liquid in reservoir 10 will cause a rise of liquid through the tube 80 28, while gas in the gasometer is prevented from escaping through tube 28 by the liquid in the latter. The tube 27 28 29 can be secured to bottom 2 to accompany reservoir 10, and the branches 28 29 being outside shell 4 85 90 are readily accessible.

The generator 20 is shown with side lugs 31 to enable the device to be set into a hollow holder or foot 32; but any other suitable support can of course be used for the device. 95 The reservoir 10 being separate from the outlying seal 5 4 the respective liquids are kept separate. In place of spring 12 the arm 14 could be made to overweight or close door 11; but a spring 12 has been found practical.

100 What I claim as new, and desire to secure by Letters Patent, is—

1. A gas-generator comprising a gasometer, a holder for carbide mounted on and made to

move with the gasometer, a door or outlet provided with an arm, a reservoir in the gasometer under the holder, and a tubular standard secured in the reservoir adapted to be engaged by the arm to open the door and having its lower part broken or open to communicate with the reservoir substantially as described.

2. A gas-generator comprising a gasometer, 10 a holder for carbide carried by the gasometer, a door actuated by the holder, a reservoir, a seal for the gasometer, a cleaning-tube lead-

ing into the lower part of the reservoir and provided with a valve and a filler and safety tube branched upon said cleaning-tube and extending along the outside of the seal substantially as described. 15

In testimony whereof I have hereunto set my hand in the presence of two subscribing witnesses.

OLIVER J. MOUSSETTE.
